FIG. 2

FIG. 1

FIG. 3

*INVENTOR
LEGENDRE CINQ-MARS*

by Mrs. Wright;

ATTR'Y.

UNITED STATES PATENT OFFICE.

LEGENDRE CINQ-MARS, OF SAN FRANCISCO, CALIFORNIA.

GAS-RADIATOR.

1,339,944.

Specification of Letters Patent. Patented May 11, 1920.

Application filed April 2, 1918, Serial No. 226,143. Renewed September 22, 1919. Serial No. 325,523.

To all whom it may concern:

Be it known that I, LEGENDRE CINQ-MARS, a citizen of the United States, residing at San Francisco, in the county of San Francisco and State of California, have invented new and useful Improvements in Gas-Radiators, of which the following is a specification.

The present invention relates to that class 10 of gas radiators in which the gas burner and combustion chamber are centrally located and the products of combustion pass outwardly through the tops of side members and inwardly through the bottoms of said 15 side members.

One object of the invention is to provide a gas radiator so constructed that, when the gas is first ignited, the flame cannot be extinguished by the pressure of the column of 20 cold air in the stack, or other back pressure if a stack be not used.

A further object is to provide, in use with such a radiator, means whereby a back draft in the stack or other back draft will escape 25 into the room without affecting the combustion at the burner.

A further object is to provide, in use with such a radiator, means whereby a back draft in the stack or other back draft will promote 30 a circulation of the heated products of combustion through the radiator in the proper direction.

A further object is to provide, in such a radiator, an outlet into the room which 35 will permit the escape of the air in the radiator, when it cannot otherwise escape, as, on account of the pressure of the column of cold air in the stack the escape of air thus permitting the products of combustion to 40 pass freely through the radiator.

A further object is to provide, in such a radiator, means for quickly expelling said column of cold air, or for heating the same to such a temperature as to produce the normal 45 draft in the stack.

A further object is to provide means for preventing the stack temperature becoming unduly high, with attendant loss of heat.

Other advantages will appear from the 50 description of the invention hereinafter set forth, and will be particularly pointed out in the claims.

In the accompanying drawing, Figure 1 is a front view of my improved gas radiator; 55 Fig. 2 is a vertical central transverse section thereof on a larger scale; Figs. 3, 4, 5, are

sections on the lines 3—3, 4—4, 5—5—of Fig. 2.

Referring to the drawing, 1 indicates my improved radiator, comprising a central 60 radiating member 2 and side radiating members 3 connected together by rods 4 and communicating with each other at the top and bottom in the usual manner.

The products of combustion flow from 65 the bottoms of the side members 3 into a conduit 8 within the lower portion of the central member 2, said conduit leading out at the back of the bottom of said central member, and then upwardly, and communicating 70 at the top with the mouth of a tapering guide 9, and thence to the stack 11.

In the lower part of the central member 2 is a gas burner 12, having a central air passage, and supported by a gas pipe 13 75 screwed thereto, extending through an air opening 14 in the bottom lower end of the central chamber, and connected through a valve 16 with a source of supply of gas. Secured to bosses 17 formed on the inner 80 surfaces of the sides of said central member are angular plates 18, on which are supported the four corners of a hood or shield 19, which also serves as a deflector, preventing the flames of the burner from being 85 extinguished by the products of combustion descending thereon in the central chamber when the burner is first ignited and said products are not able to flow by their normal path through the side members 3 and up 90 the stack.

Said products of combustion are deflected by said hood or deflector 19 and caused to pass partly through holes 21 in the side of the central member and thence into the 95 room which is being heated, and partly through an elongated hole 22 in a wall 23 of an air-heating conduit 24 located within the rear lower portion of the central member, said products thus passing by said conduit 24, either by a horizontal conduit 26 communicating with said tapering guide 9, or, if the pressure in the stack be too great, downwardly by a hole 27 at the bottom of said conduit 24 into the room. In this way, 105 when the gas is first ignited, and the pressure of the cold air in the stack is too great to permit the products of combustion to flow in their normal manner through the side members and thence into the stack, said 110 products of combustion will not extinguish the flames but will escape into the room

until such time as the temperature in the stack becomes sufficiently high to permit the products of combustion to flow thereinto.

The holes 21 admit secondary air for combustion to pass into the combustion chamber over the hood 19, while said hood prevents the flames from passing directly out through said holes 21.

Should the products of combustion be able 10 to flow in their normal path outwardly through the tops of the side radiating members 3 and inwardly through the bottom of said members, but not be able to overcome the pressure of the cold air in the stack, 15 they would flow upwardly by the conduit 8 and thence by the conduits 26, 24, and out of the room by the hole 27.

Very soon after the gas is ignited, however, the air in the conduit is sufficiently 20 heated to start moving upwardly the column of cold air in the stack. The continued upward motion in the stack and the motion of the air into the mouth of the converging guide 9 produces a suction in the 25 upper portion of the conduit 24, and causes the products of combustion to circulate through the end radiating members and to pass upwardly in the stack.

In case of a back draft in the stack the 30 converging guide 9 serves to increase its velocity when leaving the guide, and thus by forming a jet across the conduit 8 creates an upward suction in said conduit and into the conduit 26, then down through the conduit 24 into the room, and thus promotes normal circulation in the radiator.

The conduit 24 is of advantage when the burner has been well started and the products of combustion are flowing in their nor-

mal paths outwardly through the tops of 40 the side radiating members and inwardly through their bottoms and thence by the conduit 8 and up through the stack, as it causes a certain amount of comparatively 45 cold air to be drawn up through the air conduit 24, which mingles with the products of combustion in the stack and reduces the temperature of the stack.

In addition, this construction is of advantage since this current of air in the conduit 24 draws off the impure air in the bottom of the compartment through the hole 27.

I claim:—

1. A gas radiator having a central member, side radiating members communicating 55 at the top with the central member, a discharge conduit leading outside of the central member and communicating with the bottoms of the side radiating members, an air-heating conduit communicating with the atmosphere and with the discharge conduit, and a converging guide located in said discharge conduit opposite to its juncture with said air conduit.

2. A gas radiator, having a central member, side radiating members communicating 65 at the top with the central member, a discharge conduit communicating with the bottoms of the side radiating members, and leading outside of the central member, first, 70 upwardly and then changing its direction, and an air heating conduit communicating at a lower point with the atmosphere and at an upper point with the part of the discharge conduit at which it changes its direction.

LEGENDRE CINQ-MARS.
